UNITED STATES PATENT OFFICE.

CHARLES WASEIGE, OF BILLANCOURT, FRANCE, ASSIGNOR TO SOCIÉTÉ DES AERO-PLANES HENRI & MAURICE FARMAN, OF BILLANCOURT, FRANCE, A CORPORATION OF FRANCE.

SHOE BRAKE.

Application filed February 9, 1921, Serial No. 443,556, and in France February 19, 1920.

This invention relates to brakes of the kind called shoe brakes; and one object is to ensure their energetic action in both directions of driving, whether forward or backwards, with a minimum of effort on the part of the driver.

Generally speaking, the brake according to the invention comprises a plurality of novel shoes of aluminium or the like faced with a metalloplastic band of asbestos and brass or other suitable material. These shoes are connected, as by a pivot, to each other, without a fixed anchor on the brake supporting plate or disc. At the end of each of the 15 shoes opposite the joint or connection above referred to, may be mounted a steel plate provided with bosses engaging with the control cam and the ends of said plates are cut out to pivot about the spindle of the cam.

20 In the accompanying drawings by way of example,

Figure 1 shows an elevation of the brake according to the invention, in vertical section through the drum and just inside the wheel, 25 to show the shoes in side elevation.

Figure 2 shows a vertical section through the vertical diameter of the brake.

Figures 3 and 4 are detail views of the joints.

30 Figure 5 shows a constructional modification of the device shown in Figure 1, in which the cam of the brake is single instead of double.

Figure 6 is a detail view of the joint of the cam corresponding to the brake of Figure 5.

In the construction shown in Figures 1 and 2, the brake is constituted as follows:

The bosses 5' and 13' of the two plates 5 and 13 secured to the shoes 1 and 3, are in permanent contact with the double cam 2 owing to the tension of the main spring 6 which urges the two shoes toward each other. The latter are pivoted or otherwise connected at 12, but without a fixed anchor on the support or disc 4. The latter disc carries the brake control, which is secured to the axle and does not rotate. The drum 7 is secured to the wheel. When the double cam is operated, the shoes are moved apart and brake the drum. The plates 5 and 13 are cut out at the end so as to engage with and be guided by the spindle 15 of the cam.

If the cam 2 is operated whilst the wheel

is rotating in the direction of the arrow, the two shoes are spread out and, owing to their adhesion to the drum, they tend to rotate in the same direction. The thrust from shoe 1, tends to be transmitted to the cam 2, but since the shoe 1 straddles and is guided by the spindle 15, a great part of the thrust on the cam is transferred to the spindle so that the shoe 1 acts to a great extent as if it were actually pivoted on said spindle and thus the actuating force necessary to operate the cam is materially reduced. The shoes tend to open, and automatically increase the braking action (Fig. 1) exactly as in a brake with pivotally anchored shoes. Nevertheless, with the latter, the shoe is urged inwardly by the adhesion or friction of the drum when the wheels rotate in the direction opposite to that of the arrow, and only the force applied to the control lever of the cam, ensures the braking. This disadvantage cannot exist in the brake construction with a double cam, the position of the shoes remaining the same in one direction as in the other. Preferably there are a pair of cams 2 on opposite sides of, and laterally guiding, the interfitting ends of the shoes (see Fig. 3), and engaging pairs of pins projecting laterally of the shoes.

The joint 12 being perfectly free, the braking action of each shoe is the same, since they balance each other, unlike in brakes with shoes anchored at a fixed point. In this latter case each of the shoes acts, in fact, independently of the other.

As soon as the braking is finished, the auxiliary spring 8 secured at one end to the shoe 1 at 10, and at the other end to the disc 4 at 11, pulls the shoe back to the supporting face of a stop 9 adjustable from the outside of the drum by means of a screw and nut. The adjustable stop 9 comprises a screw member secured at its inner end to the shoe 1 and at its outer end extends through a bracket on the fixed disc 4. On the screw member, outside of the bracket, is a nut for adjusting the length of said member inside of the bracket. By such adjustment the normal separation of the shoe 1 from the drum by the spring 8 can be regulated to provide more or less clearance between the two. The spring 8 normally pressing the shoes together on the cam, the spring 8 under tension connecting the shoe 1 with the

cover disc and the adjustable stop 9 provide a resilient or floating suspension of the shoes within the drum, and by adjusting the stop 9 the relative positions of the shoes and 5 drum can be regulated to meet the requirements. The slight looseness of stop 9 which is almost unavoidable in manufacture is sufficient to permit the slight lengthwise movements of shoe 1 as the brake is applied, 10 whichever direction the drum may be turning.

The spring 6, intending to pull back together the two shoes, produces a sudden disengagement of the same from the drum.

15 The auxiliary spring 8 not only cooperates with the stop 9 to determine the idle position of the shoes, but also insures engagement of shoe 3 with the drum prior to full engagement of the drum by shoe 1, the circumferential movement of shoe 3 caused by the friction of the drum serving to overcome spring 8 and force shoe 1 against the drum. When 20 the vehicle is moving forward and the drum is turning in the direction of the arrow, this 25 successive action of the shoes is especially efficient and desirable.

In the modified construction shown in Figure 5, the whole of the brake construction is generally the same as that described in the foregoing: The only difference 30 consists in the substitution for the double cam 2, Figure 1, of a single cam 14. As shown later on, this form offers certain advantages, but the braking is not exactly the 35 same in the two directions.

The shoe 1 is in this case pivoted at one of its ends on the spindle 15 of the cam 14. It is coupled to the shoe 3 by a free joint 12 at its opposite end, as in the construction 40 shown in Figure 1.

The shoe 3 carries a cut out plate 16, always held in engagement with the cam 14 by means of the return spring 6.

45 The working is as follows: The wheel rotating in the direction of the arrow, if the cam 14 is operated, the joint of the two shoes 1 and 3 being free, the shoes have the tendency to open out and to engage automatically with the drum, thus increasing 50 the braking effort produced by the rotation of the cam as in the brake previously described.

The thrust on the shoes being transmitted directly to the spindle of the cam, and not 55 to the cam and spindle as in the case of the brake with a double cam, it follows that the said brake has the advantage of requiring a still smaller effort at the brake lever for producing as effective braking as in the preceding case, but, as already stated, the braking 60 cannot be exactly the same in both directions.

From what has been stated, it follows that 65 this brake makes it possible to obtain equal braking in the first case, or an almost equal

braking in the second case, whether driving forward or reversing. The single friction device constituted by two parts pivoted to each other, is expanded at the moment of braking on the whole inner surface of the 70 drum, whilst in existing brakes of the said type, the braking depends on the fixing, during the machining, of the axes of the joints, and it may happen that the shoes open in a manner non-concentric with the brake drum. 75 In the case of a brake according to the invention, the contact surface is a maximum as in band brakes, the effort required for a good braking is therefore a small one.

Claims—

1. In combination with a drum and a fixed disc cover therefor, an internal brake for engaging the drum consisting of two articulated shoes, an operating spindle and cam disposed between the unconnected ends of said brake shoes and so arranged that the braking reaction is transmitted to the spindle, a spring connecting the two shoes and normally tending to draw them toward the cam, and a second spring connecting one shoe 90 with the disc cover and normally tending to separate this shoe from the drum, independently of the other brake shoe. 80

2. In a brake, the combination with an external drum and a fixed disc cover therefor, of a pair of brake shoes pivoted together at one of their ends and arranged within the drum and operative when opened to frictionally engage the inner periphery of said drum, a spindle mounted between the free ends of the brake shoes, a cam on the spindle between the free ends of the brake shoes to be rotated by the spindle to separate the shoes to effect frictional engagement between the shoes and the drum, a spring connecting the two shoes and normally tending to close the same on the cam, a second spring connecting one of the shoes with the disc cover and normally tending to separate said shoe from the drum, and an adjustable stop to limit the separation of the shoe connected with the second spring from the drum. 95

3. In a brake, the combination with an external drum, of a pair of pivoted brake shoes arranged within said drum, a spindle mounted between the free ends of the brake shoes, said free ends being bifurcated to straddle said spindle, a cam mounted on said spindle each side of the free ends of the shoes and cam engaging projections carried by said ends between which said cams are positioned, whereby, upon the turning of the cams, the free ends of the shoes will be forced apart, causing the engagement of said shoes with the brake drum. 100

4. In a brake, the combination with an external drum and a disc or cover therefor, of a pair of pivoted brake shoes arranged within said drum adapted to engage the inner periphery thereof, a spindle mounted be- 115 120 125

tween the opposite free ends of the brake shoes, said free ends being bifurcated to straddle said spindle, oppositely disposed bosses or projections carried by said free 5 ends, a cam mounted on the spindle between the bosses of the opposite free ends, and a spring arranged to maintain the free ends of the shoes in contact with the cam.

5. In combination with a drum, an internal 10 brake for engaging the drum consisting of, two connected shoes, expanding means adjacent the ends of said brake shoes, anchoring means taking the torque from one shoe when the drum is turning in one direction and from the other shoe when the drum is turning in the other direction, a spring connecting the two shoes, a stop engaging one of the shoes, and a second spring urging said shoe against the stop.

20 6. In combination with a drum, an internal brake for engaging the drum consisting of a plurality of connected shoes having two separated ends, expanding means acting on said separated ends, the expanding means 25 being arranged to take the braking torque from one shoe when the drum is turning in one direction and from the other shoe when the drum is turning in the opposite direction, and a spring normally tending to hold 30 said ends in engagement with the expanding means.

35 7. A brake comprising, in combination, a drum, a plurality of connected rigid shoes arranged within the drum to wrap with a self-energizing action against the drum in either direction of drum movement, and spreading means acting on the unconnected ends of the shoes and arranged to take the braking torque from one of said ends when 40 the drum is turning in one direction and from the other of said ends when the drum is turning in the opposite direction.

45 8. A brake comprising, in combination, a drum, a plurality of connected rigid shoes arranged within the drum to wrap with a self-energizing action against the drum in either direction of drum movement, and means between the unconnected ends of the shoes to serve as an anchor to take the braking torque in either direction of drum movement.

50 9. In combination with a drum, an internal brake therefor, having means for securing a self energizing effect in both directions of rotation of the drum comprising a plurality of articulated brake shoes with means for taking the braking torque in either direction of drum rotation and means for insuring engagement of one shoe with the drum prior to full engagement therewith of the adjacent shoe.

55 10. In a brake mechanism, a rotatable member to be braked, a brake comprising at least two articulated shoes, an operating spindle, said brake shoes having separated

ends, at least one being bifurcated and also engaging said spindle, said spindle acting to assist in positioning said shoes, and means for moving said shoes into contact with said rotatable member.

70 11. A brake comprising, in combination, a drum, a floating friction device extending approximately a full circumference within the drum and arranged to wrap against the drum with a self-energizing action in either 75 direction of drum rotation, a substantially cylindrical anchor member extending between the free ends of said device and arranged to take the braking torque from either of said ends, said ends being notched 80 out to fit over the cylindrical anchor member, and expanding means acting on said ends.

12. In a brake mechanism, including a rotatable member and a brake therefor, 85 means for obtaining a self energizing action of the brake on said rotatable member, comprising at least two articulated brake shoes having at least one free end, a cam for acting on said free end to move the brake into 90 engagement with said rotatable member, a support for the cam, said free end being guidingly supported so as to hold it in proper working relation to said cam, said guide support including the end of the other 95 shoe.

13. A brake comprising, in combination, a drum, a pair of floating shoes within the drum, means for taking braking torque from one shoe when the drum is turning in one direction and from the other shoe when the drum is turning in the other direction, and a spring and a stop cooperating to determine the idle position of one shoe, the idle position of the other shoe being determined at 105 one end by the torque-taking means and at the other end by said one shoe.

14. A brake comprising, in combination, a drum, a floating friction device extending approximately a full circumference within the drum and arranged to wrap against the drum with a self-energizing action in either 110 direction of drum rotation, an anchor member projecting between the free ends of said device and arranged to take the braking torque from either of said ends, said ends being notched out to fit over the anchor member, and expanding means acting on 115 said ends and carried by said anchor member.

15. In combination with a drum, an internal brake of the self energizing type wherein the rotation of the drum assists in applying the brake, said brake having two articulated shoes, an operating member arranged to apply said shoes to the drum, a returning spring connected between said two shoes, another spring having one end connected to one shoe near the articulated joint and the other end to a nonrotating part of the wheel 125 130

other than the second shoe, and at least one guide stop for said shoes.

16. A brake including a drum and friction means within and engageable with the drum, 5 said means comprising, in combination, a plurality of shoes, arranged end to end and extending substantially more than 180°, a connection between adjacent ends of the shoes, an operating device arranged to 10 swing one of the shoes about the connection against the drum, said shoe moving circumferentially to force the adjacent shoe against the drum, and means acting on the shoes and arranged adjacent the connection and yieldingly urging the connected end of said adjacent shoe away from the drum while the first shoe is swung against the drum.

17. A brake including a drum and friction means within and engageable with the drum, 20 said means comprising, in combination, a plurality of shoes arranged end to end and extending substantially more than 180°, a connection between adjacent ends of the shoes, an operating device arranged to swing 25 one of the shoes about the connection against the drum, said shoe moving circumferentially to force the adjacent shoe against the drum, and a spring yieldingly urging the connected end of said adjacent shoe away 30 from the drum while the first shoe is swung against the drum.

18. A brake comprising, in combination, a drum, connected shoes engageable with the drum, applying means, and a spring arranged adjacent the connected ends of the 35 shoes and insuring that said shoes will be forced successively into fully effective engagement with the drum.

19. A brake comprising, in combination, a 40 drum, connected shoes engageable with the drum, applying means, and a spring arranged to insure that said shoes will be forced successively into fully effective engagement with the drum.

45 20. A brake comprising, in combination, a drum, a plurality of connected shoes arranged end to end within the drum, and a cam acting on the free end of the end shoe, the side of the cam engaging the side of the 50 shoe for positioning said end laterally.

21. In a self-energizing brake comprising at least two articulated shoes, actuating means acting on at least one of said shoes and yielding means for ensuring the engagement of one shoe with a member to be braked previous to full engagement of another shoe.

55 22. A brake comprising, in combination, a

drum, a pair of connected shoes within the drum, an adjustable stop engaging one shoe at least in idle position, and a spring urging 60 said shoe toward the stop and overcome in applying the brake by movement of the other shoe.

23. A brake comprising, in combination, a drum, a plurality of shoes engageable with the drum and so arranged that at least in one direction of rotation of the drum one shoe forces the adjacent shoe against the drum, and means for taking the torque of said one shoe and said adjacent shoe at the end of 70 said adjacent shoe toward which the drum is in that direction turning along the shoes and for taking the torque of at least one of said plurality of shoes at the opposite end when the drum is turning in the opposite direction. 75

24. A brake comprising, in combination, a shoe having thrust parts on its opposite sides, and a pair of cams guidingly interengaging with the end of the shoe and operatively engaging the thrust parts. 80

25. A brake comprising, in combination, a pair of shoes each having thrust parts on its opposite sides, and a pair of double cams guidingly interengaging with the ends of 85 the shoes and operatively engaging the four thrust parts.

26. A brake comprising, in combination, a pair of shoes having interfitting ends to guide each other, and means adjacent said ends for separating the shoes to apply the brake. 90

27. A brake comprising, in combination, a pair of shoes having a floating connection, a stop to determine the position of one of 95 the shoes, a spring urging the shoe against the stop, a second spring engaging the other shoe and urging it toward an idle position, and means for applying the brake.

28. A brake including a shoe having thrust 100 parts on its opposite sides, in combination with an applying device engaging both of the thrust parts.

29. A brake including a shoe having thrust parts on its opposite sides, in combination 105 with two cams, each engaging one of the thrust parts.

30. A brake including a shoe having thrust parts on its opposite sides, in combination with an applying device engaging both of the thrust parts and also arranged to prevent lateral movement of the shoe.

In testimony whereof I affix my signature.
